LETTUCE AND CARROT CRATE LINER

Benjamin Ferril Taylor and William Glen
Simmons, Salinas, Calif.

Application October 4, 1939, Serial No. 297,930

1 Claim. (Cl. 217—3)

This invention relates to shipping crates and more particularly to a liner for crates used in shipping perishable vegetables and the like.

The primary object of this invention resides in the provision of a liner for vegetable shipping crates, particularly that type used in shipping lettuce and carrots, adapted to permit icing of the vegetables packed in the crates and insulate the interior of the crate to the maximum degree against the exterior atmosphere so as to reduce melting of the ice to the minimum.

Another object of this invention resides in the provision of a liner for crates, such as lettuce and carrot shipping crates, adapted to be disposed in the crates prior to packing so crushed ice can be poured therein on top of the contents thereof without spilling on the floor.

A further object of this invention resides in the provision of a liner for lettuce and carrot shipping crates having its body portion extended above the top of the crate and adapted to be slit at certain points to permit folding thereof over the ice within the crate.

A still further object of this invention resides in the provision of a liner for perishable vegetable shipping crates formed from blank sheets of water-proof material, such as heavy waxed paper or the like, adapted to be shipped in flat condition and set up in the crates prior to packing.

Aside from the foregoing objects this invention resides in the particular construction of the elements forming the liner.

Among the many objects of this invention is the particular construction of the bottom so as to completely cover the lower open corners of the crates.

One of the salient features of this invention resides in the provision of a liner for lettuce shipping crates having a certain area thereof protruding from the top of the crate during packing thereof so as to prevent bruising of the top layer of the lettuce by the packer and when the lid is compressed into place for securing to the crate.

Included among the important objects of this invention is the provision of a liner, for lettuce shipping crates of the slat type, adapted to protect the lettuce from damage by being partly pushed through the slats during compression of the contents of the crate while securing the cover thereon.

With these and other objects in view this invention resides in certain novel features of construction and arrangement of elements to be hereinafter more particularly set forth in the 55

specification, illustrated in the accompanying drawings and pointed out in the appended claim and, while this disclosure depicts our present conception of the invention, the right is reserved to resort to such changes in construction and arrangement of elements as come within the scope of the claim.

In the accompanying drawings forming a part of this application

10 Figure 1 is a plan view of a conventional vegetable shipping crate showing its cover removed and the liner disposed therein with its flaps in closed position.

15 Figure 2 is a side view thereof showing certain parts broken away to better illustrate the assemblage thereof.

20 Figure 3 is an enlarged longitudinal vertical sectional view approximately on line 3—3 of Figure 1 showing the crate packed and open in full lines and closed in dotted lines.

25 Figure 4 is a perspective view of the side and bottom in juxtaposition.

Figure 5 is a plan view of the blank forming the side portion of the liner.

25 Figure 6 is a detail perspective view of the blank forming the bottom of the liner.

Figure 7 is a detail sectional view of a portion of the lower side of the crate taken on line 7—7 of Figure 2.

30 In the present illustration of this invention the numeral 5 designates, in general, a liner to be inserted in perishable vegetable shipping crates before packing, such as those used in shipping lettuce and carrots, and consists of a side portion 35 6 and a bottom portion 7.

The side portion 6 is preferably formed from an elongated sheet of heavy but flexible water-proof material, such as waxed paper or the like, and is scored along the lines 8 to form side and end members 9 and 10, having flaps 12 formed by scoring the material on the line 11 and slitting it along lines 13.

40 Formed on one edge of the sheet of material is an extension equal in height to the side and end members, the same forming a corner flap 15, as by scoring the material on line 14, to permit folding over the free end of the opposite side portion prior to inserting the liner in crates.

45 The bottom portion 7 is formed of a sheet of material similar to that used in constructing the side portion 6 and has its corners cut out as at 16 and scored along the lines 17 to provide sides 18 and ends 19 when folded, the former of which are preferably of greater width than the latter to completely cover the open areas indicated

by the letter A between the lowermost side slats of the conventional crates indicated by the letter C to prevent said sides from straightening out under pressure from the contents of the crate.

Prior to packing the crates the bottom 7 is folded to form a tray which is disposed on the bottom thereof, whereupon the side portion 6 is folded into substantially rectangular configuration and inserted within the crates with its lower end seated in the tray and its flap carrying portion protruding approximately two inches beyond the top of the crate as indicated by the letter T on the drawings. With the liner thus disposed in the crates, lettuce, carrots or other varieties of perishable vegetables are packed in the usual manner without bruising the same leaving a space beyond the top of the crate and above the top layer of the vegetables to accommodate the top layer of crushed ice, the protruding sides of the liner also act to prevent spilling of the crushed ice on the floor while being poured over the vegetables and during compression of the contents of the crate prior to securing the cover thereon.

Subsequent to completely packing and icing the contents of the crates, the flaps are folded over the ice whereupon the usual crate cover is placed thereon and nailed or otherwise secured to the crate after compressing the contents in the usual manner.

With this invention fully set forth it is manifest that a liner for perishable vegetable shipping crates is provided which will readily perform the functions of its adoption and, through the simplicity of construction thereof, it can be cheaply manufactured and shipped in knock-down condition for future assemblage by unskilled labor.

Having thus described our invention what we claim and desire to protect by Letters Patent is:

The combination with a skeleton crate having vertically spaced end slats disposed inwardly of the crate and lower side and bottom slats disposed remote from its lower side corners, a tray 15 formed of heavy waxed material having up turned sides of greater height than its up turned ends, the former of which and adjacent portions of the bottom thereof closing the spaces between the lower side and bottom slats of the crate while 20 the latter of which bear against the vertical end slats, a liner formed of heavy waxed material disposed in the crate with its lower edge resting in said tray against the sides and ends thereof with its upper portion extending above the top 25 of the crate and flaps falling on the upper edge of the liner.
